UNITED STATES PATENT OFFICE

FRANK H. LACH, OF CHICAGO, ILLINOIS

BODY-DRYING IMPLEMENT

Application filed July 25, 1928. Serial No. 295,329.

This invention relates to improvements in body driers, and more particularly to implements for removing water and moisture from the body, as for instance after bathing 5 and in lieu of a towel.

The object of the invention is to provide a drying implement which will effectively and quickly remove water from all parts of the body, at the same time stimulating the circulation by reason of the pressure applied as the implement passes over the body.

A further object of the invention is to provide in a single implement a plurality of flexible drying surfaces or edges of different contour, so that all portions of the body may be dried with equal facility.

A preferred form of the drying implement is disclosed in the accompanying drawings, in which

20 Figure 1 is a perspective view of a preferred form of the device.

Figure 2 is an enlarged view in elevation of the main portion of the device.

25 Figure 3 is a view in vertical section taken on line 3—3 of Figure 1, and

Figure 4 is a perspective view of a modified form of the device.

The implement comprises in general a flat body portion 1 of a non-resilient material and 30 a marginal portion 2 of a resilient material, such as rubber, the latter being divided into sections—four in number—presenting edges of different contours. The body portion may be made of any suitable material such as 35 a light metal (aluminum being preferable), hard rubber, bakelite or other composition.

As preferably made, the body portion resembles two thin plates with a space of say one-eighth of an inch separating them, except at their central portion where they are joined together by an integral section 1^a of 40 rectangular shape. Thus the edges of the body member present deep slots from which project the marginal portions of the flexible material, a sheet of rubber of say one-eighth of an inch in thickness being preferably used. The edges of the body portion and those of the flexible material have the same contour, each edge varying in some degree from the others, for instance, two opposite edges 2^a, 2^a

will be concave but differing in the amount of concavity, whereas of the remaining two edges one 2^c will be straight and the other 2^d convex. In this manner a flexible edge or strip is provided for all of the various surface contours of the body. Moreover, by having the edges of the body portion conform to the contour of the adjacent edges of the resilient material, the width of the projecting strip of flexible material is uniform 55 throughout, so that there is the same degree of flexibility present along each edge as it is pressed against the particular area of the body being dried. The flexible material or rubber sheet 2 is firmly held within the slots 60 or spaces between the two side plates of the body portion, its central portion being cut away to fit around the central core of the body portion. If desired, the body portion 65 may be made in two parts or plates, the sheet of rubber placed between, and rivets or other fastening members inserted through these layers of material.

The implement as thus designed is held in one hand and then the other, being held edge-wise against the body and moved with a scraping motion over the wet skin with sufficient pressure to expel all of the moisture from the pores and recesses in the skin, the water accumulating ahead of the contacting edge and thence shaken off at the end of each drying stroke. The implement is turned in the hand as the drying proceeds, so that the proper edge is presented for the effective 70 drying of all surface contours.

In order that the implement may reach parts of the body otherwise unaccessible, an extension handle 3 is provided having a threaded end of reduced diameter at one end, which screws into a tapped hole or socket at 75 the center of the implement body. This handle may be of any desired length or adjustable as to length by making it in sections which fasten together end to end by screw-threaded connections or otherwise.

As a modification of the implement, Figure 4 illustrates a type in which the same features are present, although the arrangement is somewhat different. The body portion 4 in this instance is in the shape of a 80

cross, with the several slotted edge portions extending radially and spaced apart at 90° from each other. These edge portions retain the strips of flexible material 5, each 5 having a different contour conforming to that of the edge portion in which it is held. The handle 3 in this instance is attached at one end of the body portion and projects axially therefrom.

10 An implement of this character can also be made in other forms or styles without departing from the purpose and manner of use of the implement and therefore I do not wish to be limited to any specific design or construction except within the scope of the 15 claims.

I claim as my invention:

1. A drying implement for the purpose described comprising a body having a plurality 20 of slotted edge portions of different contour, strips of flexible material secured in said edge portions, with marginal portions of substantially uniform width projecting therefrom, and having their edges conforming to the 25 edge contour of its associated edge portion.

2. A drying implement for the purpose described comprising a body having a plurality of blade-like portions each having a different edge contour, and strips secured along the 30 edges of said blade-like portions and projecting a substantial distance therebeyond, with their edges conforming to the edge contour thereof.

Signed at Chicago, Ill., this 18th day of 35 July, 1928.

FRANK H. LACH.
